CLAIM

(21) Appl. No.: **29/439,856**

I claim the ornamental design for a hybrid TV set top box with a wireless, touch based remote control, as shown and described.

(22) Filed: **Dec. 17, 2012**

DESCRIPTION

(51) **LOC (10) Cl.** **14-03**

FIG. 1 is a front view of a hybrid TV set top box with a wireless, touch based remote control showing our new design;

(52) **U.S. Cl.** **USPC** **D14/125**

FIG. 2 is a back view thereof;

(58) **Field of Classification Search**

FIG. 3 is a right view thereof;

USPC D13/168; D14/218, 125; 315/158, 295;
340/4.3, 4.42, 12.22, 12.23, 12.24,
340/12.29, 12.3, 13.2, 13.21, 13.24;
341/176; 345/169; 348/734; 455/352;
463/39; 700/17, 65, 83

FIG. 4 is a left view thereof;

See application file for complete search history.

FIG. 5 is a top view thereof;

(56) **References Cited**

FIG. 6 is a front isometric view thereof;

U.S. PATENT DOCUMENTS

FIG. 7 is a back isometric view thereof;
